UNITED STATES PATENT OFFICE.

NIMROD W. L. BROWN, OF MARIETTA, GEORGIA.

OIL-PRESS BOX.

1,114,106.

Specification of Letters Patent.

Patented Oct. 20, 1914.

Application filed January 7, 1913. Serial No. 740,638.

To all whom it may concern:

Be it known that I, NIMROD W. L. BROWN, a citizen of the United States, residing at Marietta, in the county of Cobb and State of Georgia, have invented new and useful Improvements in Oil-Press Boxes, of which the following is a specification.

The present invention relates to presses, particularly to such presses as are designed for expressing fluid from oleaginous substances, such as cottonseed, flaxseed and the like, wherein a plurality of press boxes are employed within which the oleaginous matter is compressed, and from which boxes, after pressing, the cakes must be removed.

The object of the present invention is designed to facilitate the removal of the oil cake, which, owing to the pressure employed for extracting the fluid substances therefrom, is tightly packed within the press boxes and so far as known can be removed only by the use of suitable tools inserted between the cake and the box for prying the cake loose.

The present invention consists of a tool seated in the main interior pressing surface of the oil press box and adapted to be moved into the box for the purpose of forcing the cake in part or in whole from the box.

In order that the invention may be fully understood, by those skilled in the art, attention is directed to the accompanying drawing illustrative of one embodiment of the invention in which—

Figure 1 is a plan view in outline of an oil press box having the invention applied thereto. Fig. 2 is an end elevation of a portion thereof. Fig. 3 is a sectional view on the line 3—3 of Fig. 1. Fig. 4 is a view similar to Fig. 2 with the plug closure or loosening tool removed to show the window or opening in which it is seated.

In the drawings, wherein like reference characters are used to indicate the same parts in all the figures, 10 indicates a press box having a marginal wall 11 around its four sides which, as here shown, is of rectangular shape. At one end of the press box the wall 11 is pierced by one or more openings or windows 12, preferably near the corner of the box. On each side of said opening is a projecting lug 13, perforated at 14, to receive a pivot pin 15 on which a cake loosening tool 16 is hinged, said tool serving also as a plug closure for the opening or window 12. The loosening tool 16

has a finger 17 projecting inwardly through the opening or window into the box 10 and is seated normally in a notch or recess 18 formed in the main interior pressing surface 19 of the box. The underside of the finger 17 is made flush with the surface 19, as shown in Fig. 3. Exterior of the pivot pin 15 the loosening tool 16 is provided with an outwardly projecting stud 20, in which is formed a socket 21 to receive a bar or other implement for rocking the loosening tool.

Constructed as described, the material from which oil is to be expressed is compressed against the surface 19 of the press box and as the pressure applied must be great, said material is compressed into a cake which adheres very tightly to the surface 19 and sides of the press box, so that powerful leverage is required to separate the cake from the box. After the cake has been pressed and the press boxes 10 separated, a bar of suitable length is inserted in the socket 21 of the loosening tool and lifted. This lifting movement depresses the nose 17 of the tool and forces part of the cake laterally or broad face foremost away from the surface 19 and below the edge of the box, the loosening tool being preferably capable of rocking to the position indicated by dotted lines in Fig. 3.

After a corner or edge of the cake has been bent down as described, a slicing tool is inserted between the cake and the bottom edge of the box, and the cake pried away from the surface 19 in a manner well understood by those skilled in the art. The outer end of the loosening tool 16 is made heavier than the finger 17 to overbalance said finger and return the tool to normal position, retaining it in such position after the bar has been removed from the socket 21.

I claim:

1. A press box having a wall provided with an aperture, and a rocking closure within said aperture projecting into the box and hinged thereto.

2. A press box having a wall provided with an aperture, and a loosening tool serving as a rocking closure for said aperture projecting into the box and hinged thereto so that it may be rocked and its inner end swung into the cavity of said box.

3. A press box having a wall provided with an aperture, and a loosening tool projecting through said aperture into the box and hinged thereto, said tool remaining in

said box while the contents thereof are under pressure and adapted to be rocked to swing its inner end into said box.

4. A press box having a wall provided with an aperture, and a loosening tool projecting through said aperture into the box and hinged thereto, the end of said tool within the box fitting a recess in the box and conforming to the inner surface thereof and adapted to be rocked to force a portion of the contents of the box therefrom.

5. A press box for oil presses having a wall provided with an aperture, a cake loosening tool projecting through said aperture into the box and serving also as a closure for said aperture, and a hinged connection between the tool and the box to permit said tool to rock and force an edge of the cake face foremost from the box.

15 6. A press box for oil presses having a wall provided with an aperture, a pivotally mounted cake loosening tool projecting part way into said box through said aperture with its inner end seated in a recess in the box and made flush with its inner surface, and means at the outer end of said tool to receive a rocking device for tipping said tool to press its inner end against the cake and separate it from the box.

25 7. A press box for oil presses having a wall provided with an aperture, a cake loosening tool hinged on said box and projecting through said aperture, the inner end of said tool being seated in a recess in said box and made flush with its inner surface, and means for rocking said tool to depress its inner end against the cake and separate the latter from the box.

30 8. A press box for oil presses having a wall provided with an aperture, lugs projecting from said wall, and a cake loosening tool hinged intermediate its ends between said lugs and extending through said aperture into said box.

40 45 9. A press box for oil presses having a wall provided with an aperture, lugs projecting from said wall, a cake loosening tool hinged between said lugs and extending through said aperture into said box and means on the outer end of said tool by which it is rocked to loosen the cake from the box.

50 55 10. A press box for oil presses having a wall provided with an aperture, lugs projecting from said wall, a cake loosening tool hinged between said lugs and extending through said aperture into said box, and a socketed stud on the outer end of said tool by which it is rocked to loosen the cake from the box.

60 65 11. A press box for oil presses having a wall provided with an aperture and a recess continuous with said aperture, lugs projecting outwardly from said wall, a cake loosening tool hinged between said lugs and

filling said aperture, said tool having a finger projecting into the box for loosening the cake, said finger normally lying within said recess and being flush with the surface of the box, and a socketed stud on the outer end of said tool to receive a bar by means of which said tool is tilted to loosen the cake, the outer end of said tool being heavier than the inner end to normally hold the finger within the recess.

70 12. A press box having a wall provided with an aperture, and a swinging closure within said aperture projecting into said box, said closure adapted to be rocked to loosen a cake within said box by forcing said cake in whole or in part face foremost from the box.

75 13. An oil press box having a wall provided with an aperture, and a rocking cake loosening tool projecting through said aperture into the box to loosen the cake when rocked and force it face foremost from the box, said tool adapted to remain in the box while the cake is under pressure.

80 85 14. A press box having a wall provided with an aperture, and a rocking cake loosening tool projecting through said aperture into the box, the end of said tool within the box having beveled edges, the exposed portion of said end conforming with the surface of said box.

90 95 15. A press box having cake loosening means projecting into it, and a hinged connection between said box and said cake loosening means to permit the latter to rock.

100 16. A press box having cake loosening means normally serving as an abutment for the edge of the cake, and a hinged connection between said box and said cake loosening means to permit the latter to rock.

105 17. A press box having cake loosening means projecting into said box above the cake and serving as an abutment for the edge of the cake, and a hinged connection between said box and cake loosening means whereby said means may be tilted to force the cake from the box.

110 115 18. A press box having a cake loosening tool projecting into the cake recess and adapted to be tilted relative to the box to force the cake from the cake recess.

19. An inverted press box having a cake loosening tool seated in the main interior pressing surface thereof.

120 20. An inverted press box having a cake loosening tool seated in the main interior pressing surface thereof and pivoted to said box so that it may be rocked to loosen the cake.

125 21. An inverted press box having a cake loosening tool seated in the main interior pressing surface thereof and pivotally mounted thereon, said tool being adapted to have its interior end lowered into the box by rocking the same.

22. A press box having a closed interior receptacle formed by fixedly attached and downwardly projecting side and end walls, and a tool projecting through an aperture in one of said walls and having its inner end seated in the main interior pressing surface of said box, said tool being hinged to the box and adapted to have its inner end lowered into the box to force a part of a cake therefrom.

23. A press box having side and end walls to form a cake receiving cavity, and a tool projecting into said box adapted to bend an edge of a cake out of said box.

24. A press box having side and end walls to form a cake receiving cavity, and a tool seated in the main interior pressing surface of the box, extending to the outside of the box and adapted to be moved laterally from its seat within the box to loosen a part of a cake.

25. A press box having a tool projecting into and adapted to be tilted relative to the box to force an edge of a cake from the box.

26. A press box having a tool positioned in it and forming a part of it, and adapted to loosen a part of a cake by moving the same laterally within the box.

27. A press box having a tool positioned therein and hinged thereon and adapted to loosen a part of a cake by moving the same laterally within the box by a lateral movement of the tool.

28. A press box having a tool seated in the main interior pressing surface thereof and

adapted to be moved laterally from its seat into the box to move a part of a cake laterally from said box.

29. A press box having a cake loosening tool projecting beside the main interior pressing surface thereof and adapted to be moved against the cake to loosen a part of the same by moving it laterally, said tool also projecting beside an edge of the cake receiving space of the box and adapted to serve as an abutment for the edge of the cake within the body.

30. A press box having a cake loosening tool hinged thereto seated in the main interior pressing surface thereof and extending to the outside of the box, the outer end of said tool being heavier than its inner end to normally hold said inner end seated in said main interior pressing surface.

31. A press box having a wall with an aperture therein, and an outwardly opening hinged closure for said aperture provided with a cake loosening tool on its inner end adapted to seat in the main interior pressing surface of said box and hinged thereto to permit rocking for the purpose of loosening a part of a cake within the box.

In testimony whereof I have hereunto set my hand in presence of two subscribing witnesses.
